UNITED STATES PATENT OFFICE.

WILLIAM F. GROGAN, OF SCRANTON, PENNSYLVANIA.

SAFETY-RAZOR HONE.

1,424,246.

Specification of Letters Patent. Patented Aug. 1, 1922.

Application filed October 15, 1919. Serial No. 330,784.

To all whom it may concern:

Be it known that I, WILLIAM F. GROGAN, a citizen of the United States, residing at Scranton, in the county of Lackawanna and 5 State of Pennsylvania, have invented certain new and useful Improvements in Safety-Razor Hones; and I do hereby declare the following to be a full, clear, and exact description of the invention, such as 10 will enable others skilled in the art to which it appertains to make and use the same.

This invention relates to hones and particularly to hones made in sections for sharpening safety razors.

15 An object of this invention is to provide a hone that can be conveniently carried around and that will sharpen both sides of the blade at once, and that will be divided at the razor edge so as not to destroy the fine edge of the 20 razor, and that is of simple form, and that can be quickly and cheaply made, and that is of such a design as will be attractive and readily salable.

With these and other objects in view, the 25 invention consists of the construction, combination and in detail of arrangements of parts as hereinafter more fully described and claimed.

30 In the drawings:

Figure 1 is a side elevation of this hone.

Figure 2 is a vertical sectional view of this hone.

Figure 3 is a top view of Figure 1.

Figure 4 is a side elevation of one of the sections of this hone.

35 In detail the invention consists of a pair of semi-circular stones or other suitable abrasive material of suitable fine grain for use as a razor hone, although this structure is not limited to razor hones and may be used 40 for other sharpening devices, each of which stones is indicated by the numeral 1, and a casing indicated by the numeral 2 for holding said stones in proper relation. These stones are beveled from a line through their 45 diameter outward and upward at such an angle as to adapt to the angle of the razor blade to be sharpened. The casing is a drawn or otherwise fabricated brass nickel plated casing, although it may be made of 50 any other suitable and practical material.

55 In operation the casing is held between the fingers and the blade drawn between the two pieces of stone through the recess created by the bevel on the two said stones.

I claim:

The combination with a holder comprising a cylinder, of a pair of semi-cylindrical abrasive members fitted therein and projecting therefrom at one end, the outer end portions of said members being beveled on their 60 inner faces to define an acute angle between them.

In testimony whereof I affix my signature.

WILLIAM F. GROGAN.
